[57] CLAIM

The ornamental design for a stringed musical instrument, as shown and described.

DESCRIPTION

FIG. 1 is a top, front perspective view of a stringed musical instrument stand showing my new design;
FIG. 2 is a front elevational view at a reduced scale;
FIG. 3 is a rear elevational view thereof;
FIG. 4 is a side elevational view thereof;
FIG. 5 is a side elevational view opposite of that shown in FIG. 4;
FIG. 6 is an enlarged bottom plan view; and,
FIG. 7 is a top plan view thereof.
